His Attorney.

UNITED STATES PATENT OFFICE

ROYCE A. BEEKMAN, OF SCHENECTADY, NEW YORK, ASSIGNOR TO GENERAL ELECTRIC COMPANY, A CORPORATION OF NEW YORK

POWER SYSTEM

Application filed November 30, 1927, Serial No. 236,839. Renewed April 11, 1930.

My invention relates to improvements in power systems for ship propulsion and more particularly to means for operating the auxiliary equipment of ships of the direct drive type. In ship propulsion systems of the direct drive type the ship's propeller or propellers are driven from a main prime mover through a mechanical transmission. A common arrangement for such a drive is through suitable reduction gearing. The propeller for efficient operation must be driven relatively slowly whereas certain types of prime movers can be built to operate most efficiently when running at relatively high speed, for this reason double reduction gearing is usually provided where the main prime mover is a steam turbine. Some other types of prime movers can be operated at relatively lower speed but whatever the type of prime mover and whatever type of mechanical transmission may be provided for driving the propeller directly from the prime mover a great deal of auxiliary equipment is required on the ship. For example where the prime mover is a steam turbine, boiler feed pumps must be provided for maintaining the necessary level of water in the boilers for generating the steam for the turbine and much other auxiliary equipment provided. Such equipment may comprise fans for controlling the draft under the boilers, circulating and hot well pumps for the condenser, fans for ventilating the ship, apparatus for handling the cargo and devices for lighting the ship, etc. If the auxiliary equipment is operated by small steam turbines or reciprocating engines the expense of operating the ship becomes relatively heavy by reason of the fact that such small engines are relatively inefficient. The main turbine being a larger unit can be designed to operate much more efficiently than such smaller units.

Ships have been provided with electrically operated auxiliaries, an auxiliary prime mover being provided to drive a generator which supplies motors for operating the various elements of the equipment. This arrangement secures some increase in efficiency since a single prime mover which sup-

plies power for all of the auxiliary load will be considerably larger and more efficient than individual prime movers which would be used for operating the respective devices.

According to my invention the auxiliaries are electrically operated but during most of the time that the ship is in operation the power for driving such auxiliaries is derived from the main turbine which drives the ship's propeller. Since in direct drive ships as distinguished from electrically driven ships there is no main generator, I provide a generator driven either from the main prime mover shaft or from some element of the gearing between such prime mover and the propeller. If the main prime mover is normally operated at a very high speed it is advantageous to drive the generator from one of the intermediate gears since the generator may be more readily designed for a moderate speed of operation.

One of the difficulties encountered in attempting to operate the auxiliary equipment from a generator driven from the prime mover of a ship propulsion system is due to the fact that the speed of the prime mover varies through a wide range. The speed of the prime mover may be adjusted by a throttle valve or the like. In steam turbine driven ships of the electric drive type for example it is common to provide means such as a speed control lever for setting a speed governing means of the turbine. The governing means which may be of any suitable type, such as a centrifugal governor or oil pressure governor, operates to hold the speed of the turbine constant for any given setting of the speed control lever. Changes in load due to headwinds or waves or brought about by turning the ship are automatically taken care of by the speed governor, but the particular speed which is held substantially constant by the speed governor is changed by different settings of the speed lever. An example of this type of control is disclosed in Letters Patent to Emmet, No. 1,137,308, dated April 27, 1915. Since the prime mover thus operates over a wide range of speed it becomes unsuitable as a source of power for

supplying the auxiliary equipment during conditions of relatively low speed.

While a speed governor with adjustable setting is desirable as a nearer approach to an ideal system, this refinement is not at all essential to the practical application of my invention, and in ships for certain classes of service it is sufficient to use a throttle lever or the like for speed control while relying upon an emergency governor, which may, for example, be of the centrifugal type, to shut off the power if a predetermined speed is exceeded.

In accordance with my invention I supply the auxiliary equipment from a generator driven from the main prime mover while the speed of such main prime mover is suitable, and provide an auxiliary source of power which assumes the load of the auxiliary equipment when the main prime mover becomes unsuitable as a source of power and provide improved control devices for thus transferring the auxiliary load to the auxiliary prime mover. I thus secure the advantage of the more efficient operation of the main prime mover during most of the time the ship is in operation while securing reliability of service of the auxiliary equipment from an auxiliary power supply which takes up the load only when necessary.

My invention will be better understood from the following description considered in connection with the accompanying drawing and its scope will be pointed out in the appended claims.

The drawing, Fig. 1, diagrammatically represents a ship propulsion system showing one embodiment of my invention and Fig. 2 diagrammatically represents one modification thereof.

Referring to Fig. 1, a propeller 1 is diagrammatically illustrated as driven through reduction gearing from a prime mover, indicated as a steam turbine 2. A generator 3 is driven from the main turbine 2 through the intermediate gear 4 in the arrangement illustrated. The auxiliary circuit 5 is represented as connected to the generator 3 through switching means shown as comprising a circuit breaker 6. While the speed of the main turbine 2 is suitable for driving the generator 3 to supply the auxiliary equipment of the circuit 5 the circuit breaker 6 is closed. When the main turbine is operating over a range of speed unsuitable for supplying the auxiliary equipment from the generator 3 the circuit breaker 6 is open and the auxiliary prime mover, indicated as a turbine 7, operates to drive the auxiliary dynamo-electric machine 8 as a generator to supply power to the auxiliary circuit 5. While the generator 3 is supplying power for the auxiliary equipment the dynamo-electric machine 8 remains connected to the aux-

iliary circuit 5 and operates as a motor to drive the turbine 7 idle.

In the particular arrangement diagrammatically illustrated, a second turbine 2' is shown for assisting in driving the propeller 1. As illustrated this second turbine 2' is a low pressure turbine operated by steam exhausted from the turbine 2 through means indicated by the pipe 9. It is to be understood however that my invention is not limited to any particular type of prime mover nor to any particular type of mechanical transmission between the prime mover and the propeller. Means are ordinarily provided in a ship propulsion system for reversing the operation of the propeller but as such means form no part of my present invention it has not been indicated on the drawing.

The speed controlling lever for adjusting the speed of the main turbine is diagrammatically indicated at 10. As far as my invention is concerned this speed lever 10 may be regarded as a throttle lever for any suitable prime mover whether of the steam, gas or other type. In the arrangement diagrammatically illustrated it is indicated as operating through a connection 11 to adjust the governor or throttle valve of the turbine 2 which governor or throttle valve is not shown in detail, but may be considered to be represented by the part 12. The auxiliary turbine 7 may be provided with a governor represented by the part 13. This governor will preferably be adjustable according to the broad principle of the Emmet patent above referred to. The governor of the auxiliary turbine 7 is set so that it admits steam to this turbine when its speed tends to fall below a predetermined desired value.

As heretofore stated, when the speed of the main turbine falls below a value suitable for supplying the auxiliary equipment the auxiliary unit 7, 8 becomes operative to supply such equipment. The broad idea of arranging the governing means of an auxiliary turbine to admit steam thereto when the speed tends to fall below a predetermined value is old in the art. One example of such idea of means is disclosed in Letters Patent to Clarke, No. 1,185,288, dated May 30, 1916. In the Clarke arrangement a dual drive is provided for an individual unit of the auxiliary equipment of a power station. Normally such element is driven by an induction motor supplied from a power system and when the power system fails, so that the speed of the dual drive unit tends to fall below a predetermined value, steam is admitted to the turbine to take over the load of the driven element, the induction motor being then disconnected from the power system. In my arrangement the dynamo-electric machine 8 remains connected to the auxiliary circuit. While the main generator 3 is connected to 130

the auxiliary circuit, the machine 8 drives the turbine 7 idle but when the generator 3 is disconnected from the auxiliary circuit the turbine 7 drives the machine 8 as a generator to supply the auxiliary circuit.

In the preferred embodiment of my invention shown in Fig. 1, the taking over of the load of the auxiliary equipment by the auxiliary unit 7, 8 is facilitated by providing means cooperatively related to the speed control lever 10 of the main turbine for adjusting the speed of the auxiliary turbine. In the arrangement illustrated a stop device 14 is provided for engaging the lever 10 to prevent further movement in its speed reducing direction until the stop device has been moved out of the way. For example the speed lever 10 may have 20 or more points of adjustment to vary the speed of the main turbine over a range from 3600 R. P. M. down to 1200 R. P. M., and the stop device 14 may be arranged to engage the speed lever at a point of adjustment corresponding to $\frac{3}{4}$ speed, or 2700 R. P. M. In order to adjust the speed of the turbine to something below 2700 R. P. M., in the example given, the stop device 14 must be moved out of the way. In Fig. 1 I have illustrated means whereby movement of the stop device 14 opens the circuit breaker 6 between the generator 3 and the auxiliary circuit 5 and also causes steam to be admitted to the auxiliary turbine 7. To admit steam to the auxiliary turbine a connection 15 is provided between the stop device and a speed control lever 16 for the governor 13 of the auxiliary turbine 7. To open the circuit breaker 6 I provide a contact 17 on the stop device 14 which contact is opened when the stop device is moved. In the arrangement illustrated the circuit breaker 6 is of the latched-in type and when the contact 17 is opened the tripping solenoid 18 of the circuit breaker is deenergized to knock out the latch 19 and permit the circuit breaker to be opened by the spring 20. It will be apparent to those skilled in the art, however, that my invention is not limited to any particular type of circuit breaker since many examples of circuit breakers are known which may be incorporated in my arrangement to secure the cooperative relationship which I desire.

It will be observed that in the arrangement shown in Fig. 1 the control circuit for the circuit breaker 6, which control circuit leads through the solenoid 18, is connected so that it will be energized in accordance with the voltage of the generator 3 when that generator is supplying the auxiliary circuit 5. The opening of the circuit breaker is therefore made responsive to a predetermined change in the voltage of generator 3 and likewise to a predetermined change in the speed of the main turbine 2. If, for example, be-

cause of some abnormal condition the speed of the main turbine should fall to a low value notwithstanding the fact that the speed lever 10 may be within a range above that of the setting of the stop device 14, the speed and voltage of the generator 3 may be so low as to cause the circuit breaker 6 to be tripped open. If this happens the governor of the auxiliary turbine 7 will immediately cause such auxiliary turbine to pick up the load of 75 the auxiliary equipment which will thus be maintained in continuous operation.

In the drawing I have illustrated a regulating means 21 for the generator 3. This is indicated as a variable resistance in the field circuit of the generator. I prefer to make this regulating means automatic in operation so as to maintain the voltage of the generator 3 substantially constant over a considerable speed change, preferably down to a speed substantially corresponding to the setting of the stop device 14. The particular type of regulating means used is immaterial, many examples of suitable regulating means being well-known in the art. Such automatic regulating means is desirable in that it maintains the voltage impressed on the auxiliary circuit substantially constant throughout the speed range of the main turbine during which the generator 3 supplies the auxiliary circuit and thereby secures better operation of the auxiliary equipment than would be secured with a variable voltage. The opening of the circuit breaker 6 on small changes in the speed of the generator 3 is also prevented, but if the speed falls below a predetermined point the regulating means 21 will be unable to hold the voltage up and the circuit breaker 6 will open to disconnect the generator 3 from the auxiliary circuit and permit it to be supplied by the auxiliary unit 7, 8.

Since the dynamo-electric machine 8 of the auxiliary unit operates as a motor supplied from the generator 3 while that generator is supplying the auxiliary equipment and the speed of the motor decreases with a decrease in the voltage of the main generator, it is apparent to those skilled in the art that means directly responsive to the speed of the auxiliary unit may be provided for opening the circuit breaker 6 to disconnect the generator 3 from the auxiliary circuit 5. This arrangement is diagrammatically indicated in Fig. 2 where a contact 22 controlled automatically by the governor 13' of the turbine 7, as indicated by the dotted connection 23, is arranged to open automatically upon a fall in speed of the turbine. The contact 22 in the arrangement illustrated in Fig. 2 is in series with the tripping solenoid 18 of the circuit breaker 6 so that when the contact 22 opens on a fall in speed of the turbine, the solenoid 18 is deenergized to trip the circuit breaker open and disconnect the main generator from the auxiliary circuit, leaving it supplied by 130

auxiliary unit 7, 8. As in the arrangement of Fig. 1 the solenoid 18 will itself trip the circuit breaker 6 open upon a predetermined fall in voltage.

5 While I have illustrated an embodiment of my invention utilizing dynamo-electric machines of the direct current type, it will be apparent to those skilled in the art, in the light of my disclosure, that alternating current dynamo-electric machinery may be used without departing from my invention. While my invention is particularly adapted to ship propulsion systems of the direct drive type, it will also be apparent that certain features 10 of my invention are applicable to electrically driven ships. For example, the idea of adjusting the speed of the auxiliary prime mover 7 by the stop device 14, or some equivalent arrangement providing an adjustment of the admission to the auxiliary prime mover 20 cooperatively related to the speed control lever of the main prime mover, is applicable without change to an electrically driven ship and to power systems other than ship propulsion 25 systems. This feature has the advantage of adjusting the admission to the auxiliary prime mover to enable it to pick up the auxiliary load without waiting for the speed of the auxiliary unit to drop an amount sufficient 30 to cause the governor of the auxiliary unit to become effective to increase the admission. The auxiliary load may thus be taken over by the auxiliary unit with a quite negligible change in the voltage on the auxiliary circuit. Indeed the adjustment made 35 by the movement of my stop device 14 may be such as to increase the normal speed of the auxiliary prime mover 7 so that the voltage on the auxiliary circuit is actually raised somewhat above the voltage which would 40 normally exist thereon at the time the circuit breaker 6 is opened to disconnect the main generator 3.

45 From the foregoing description it is apparent that various changes and modifications may be made in the particular devices used and the arrangement and application of such devices without departing from my invention and I therefore aim in the appended 50 claims to cover all such changes and modifications as fall within the true spirit and scope of my invention which is broadly covered by claims in a copending application of Alexander Kennedy, Jr., Serial No. 230,333, for 55 power systems, filed November 1, 1927, and assigned to the same assignee as the present application.

60 What I claim as new and desire to secure by Letters Patent of the United States, is:—

65 1. A ship propulsion system comprising a main prime mover, a propeller and means for mechanically transmitting power from the prime mover to the propeller, means for adjusting the speed of the prime mover 70 through a relatively wide range to control the

speed of the ship, a generator mechanically driven from said prime mover, a load circuit having auxiliary equipment connected thereto, switching means between said generator and load circuit, an auxiliary unit 75 comprising a prime mover and a dynamo-electric machine, said dynamo-electric machine being connected to said load circuit to operate as a motor to drive said prime mover and as a generator to supply said load circuit, and means for operating said switch to disconnect the generator driven by the main prime mover from the load circuit and for increasing the speed of the auxiliary prime mover when the speed of the main prime mover driven generator is adjusted to a value 80 too low for satisfactory operation of the auxiliary equipment from said generator.

2. A ship propulsion system comprising a main prime mover and a propeller geared thereto, means for adjusting the speed of the prime mover through a relatively wide range to control the speed of the ship, a generator mechanically driven from said main prime mover, a load circuit having auxiliary equipment connected thereto adapted to be supplied from said generator, an auxiliary prime mover, a dynamo-electric machine connected to said load circuit, said auxiliary dynamo-electric machine adapted to operate as a motor to drive said auxiliary prime mover and as a generator driven thereby, and means responsive to the voltage of the generator driven from the main turbine for disconnecting said generator from the load circuit when 100 the voltage falls below a predetermined value.

3. A power system comprising a prime mover mechanically geared to a load device, means for adjusting the speed of the prime mover through a relatively wide range, a generator mechanically driven from said prime mover, a load circuit having auxiliary equipment connected thereto arranged to be supplied from said generator, an auxiliary unit 110 comprising a prime mover and dynamo-electric machine, said dynamo-electric machine being connected to said load circuit and arranged to drive said auxiliary prime mover when the voltage of the load circuit is above a predetermined value and arranged to be driven by said auxiliary prime mover and operate to supply said load circuit when the voltage of the load circuit falls below a predetermined value, and means for automatically disconnecting said generator from the load circuit when the speed of the main prime mover is below that suitable for said generator satisfactorily to operate the auxiliary equipment and regulating means arranged to maintain the voltage of said generator substantially constant for a certain range of speed variation to prevent disconnection of said generator from the load circuit upon 115 changes in speed of the main turbine within 120 130

the range of operation of said regulating means.

4. A power system comprising a main prime mover, a generator driven from said prime mover, a load circuit having auxiliary equipment connected thereto arranged to be supplied from said generator, an auxiliary unit comprising a prime mover and a dynamo-electric machine, said dynamo-electric machine being connected to said load circuit to operate as a motor to drive said auxiliary prime mover and as a generator driven by said auxiliary prime mover to supply the load circuit, a speed adjusting device for adjusting the speed of the main prime mover through a relatively wide range, a movable stop device for preventing movement of said speed adjusting device beyond a predetermined position in the speed reducing direction until said stop device is moved, speed controlling means for said auxiliary prime mover and means controlled by movement of said stop device for disconnecting said generator from said load circuit and increasing the speed of said auxiliary turbine.

5. A power system comprising a main prime mover and a generator driven therefrom, a load circuit connected to said generator, a switch between said generator and load circuit, an auxiliary unit comprising a turbine and dynamo-electric machine, said dynamo-electric machine being connected to said load circuit, a speed adjusting device for adjusting the speed of said main prime mover through a relatively wide range, a movable stop device cooperating with said speed adjusting device to limit further speed reduction of the main turbine until the stop device is moved, means controlled by movement of the stop device for speeding up the auxiliary turbine and means conjointly controlled by the voltage of said generator and by said stop device for opening said switch to disconnect said generator from said load circuit.

In witness whereof, I have hereunto set my hand this 29th day of November, 1927.

ROYCE A. BEEKMAN.
